[57] CLAIM

The ornamental design for an aquarium pump housing, substantially as shown.

DESCRIPTION

FIG. 1 is a perspective view of the aquarium pump housing showing our new design;

FIG. 2 is a top plan view thereof;

FIG. 3 is a front elevational view thereof;

FIG. 4 is a left side elevational view thereof, the right side being a mirror image of the left side shown;

FIG. 5 is a rear elevational view thereof; and

FIG. 6 is a bottom plan view thereof.

FIG. 1

FIG. 2

FIG. 3

FIG. 4

FIG. 5

FIG. 6
